UNITED STATES PATENT OFFICE.

WILLIAM J. STEWARD, OF BOSTON, MASSACHUSETTS.

COLLAPSIBLE CHAIR AND EASEL.

Application filed April 12, 1924. Serial No. 706,052.

This invention relates to an improved chair and easel particularly adapted for use by artists in sketching outdoors.

The object of the invention is to provide a cheap, strong and durable seat and easel combined, which can be collapsed and folded into very compact space and which, when positioned for use, will provide not only a support for the drawing, and a seat for the artist, but also a back for the seat, so that in the long continued sketching the same will be restful and practical in every way. Legs are provided for the chair of original and novel construction and these legs have prongs attached thereto which may be inserted in the ground to aid in holding the chair firmly in position when in use.

The invention consists in a combined collapsible chair and easel constructed as hereinafter set forth and particularly as set forth in the claims.

Referring to the drawings:

Figure 1 is a plan view of my improved easel showing the same in position for use.

Fig. 2 is a sectional elevation of the same taken on line 2—2, Figure 1.

Fig. 3 is a detail plan of one of the legs of the chair.

Fig. 4 is a rear elevation of the same as viewed from the right of Figure 1.

Fig. 5 is a longitudinal sectional elevation of the chair and easel illustrating the same in collapsed position.

Like numerals refer to like parts throughout the several views of the drawings.

In the drawings, 6 is the chair seat which is provided with a slot 7 extending longitudinally thereof with a brace 8 extending transversely thereof and fastened to the lower side of the seat. 9 is another brace extending transversely of the seat upon the underside thereof. 10 is a reduced or tongue portion provided at the rear end of the seat. 11 is a leg hinged at 12 to the brace 8 adjacent the front end of the seat. 13 and 14 are intersecting legs, the leg 14 being shown in detail in Fig. 3 and having a reduced tongue portion 15 at its lower end which projects through a slot 16 in the leg 13. The leg 13 extends upwardly above the seat 10 thus providing a back 17. Said leg 13 is also provided with a slot 18 through which the tongue portion 10 of the seat projects and the seat is locked to the back leg 13 by a wedge-shaped key 19 which projects

through the seat 10 and holds the back leg 13 firmly locked against the shoulder portions 20 of the seat.

A prong 21 is provided upon the lower end of the leg 11 and a U-shaped prong 22 is hinged or pivotally mounted upon the back leg 13, the prongs straddling the tongue portion 15 of the intersecting leg 14, as illustrated in Fig. 4. The upper end of the intersecting leg 14 bears against the underside of the seat 6, extends entirely thereacross, and is attached to the brace 9, by a hook 23.

An arm 24 is hinged at 25 to the front end of the seat 6, the lower end 26 of said arm projecting through the slot 7 and bearing against the brace 8 when the arm is in operative position, and as will be seen by reference to Fig. 2, when the arm is in operative position it projects vertically at an inclined position from the front end of the seat 6. The arm 24 is bevelled upon its opposite edges at 27 to receive a clamp 28 which may be locked to the arm 24 at different heights by a screw 29 having screw-threaded engagement with the clamp 28 and bearing against the arm 24 upon which it is slidably mounted.

The brace 9 is provided with a notch 30 into which the prong 21 on the leg 11 projects when the seat is collapsed and the parts are folded together ready to be transported from one place to another, or ready to be packed away in a small space.

The general operation of the device hereinbefore specifically described is as follows:—Assuming the parts to be in the relative positions illustrated in Fig. 2, the drawing 31, illustrated in dotted lines Fig. 2, is placed upon the seat with its lower edge resting in a groove 32 provided in the upper face of the seat 6 and extending transversely thereacross, the upper edge of the drawing being held in position by the clamp 29. When it is desired to collapse and fold up the chair and easel, the drawing is removed from the arm 24 and preferably the clamp 29 is also removed from the arm 24. Said arm is then tipped over into the horizontal position illustrated in Fig. 5, wherein it will be seen that the arm 24 enters the slot 7 in the seat and rests upon the braces 8 and 9. The leg 11 is folded upwardly in contact with the underside of the seat 6, the prong 21 projecting into the notch 30. The key 19 is withdrawn from the seat 6, the leg 14

being laid upon the back leg 13 and the different parts then bound together by a strap 33.

I claim:

- 5 1. A collapsible chair and easel having, in combination, a seat comprising a single rigid member slotted longitudinally thereof, an arm projecting upwardly from the front end thereof and constituting a support for a drawing or the like, said arm being foldable into said slot, a leg attached to the front end of said seat and a pair of intersecting legs at the opposite end thereof.
- 10 2. A collapsible chair and easel having, in combination, a seat comprising a single rigid member slotted longitudinally thereof, an arm projecting upwardly from the front end thereof and constituting a support for a drawing or the like, said arm being foldable into said slot, a leg attached to the front end of said seat and foldable against the underside thereof and a pair of intersecting legs at the opposite end thereof, one of said pair of legs extending upwardly above the seat and forming a back therefor.
- 15 3. A collapsible chair and easel having, in combination, a seat provided with a slot extending longitudinally thereof, a brace extending transversely of said seat upon the underside thereof, an arm hinged to said seat projecting above and below the same adjacent the front end thereof and constituting a support for a drawing or the like, the lower end of said arm projecting through said slot and engaging said brace when in an inclined upright position and constituting a support for a drawing or the like, a leg attached to the front end of said seat and a support for the opposite end thereof.
- 20 4. A collapsible chair and easel having, in combination, a seat comprising a single rigid member provided with a slot extending longitudinally thereof, an arm projecting upwardly from the front end thereof and constituting a support for a drawing or the like, said arm being foldable into said slot, a leg attached to the front end of said seat, a pair of intersecting legs at the opposite end thereof, one of said pair of legs extending
- 25 upwardly above the seat and forming a

back therefor, the other leg of said pair being reduced in width at its lower end and projecting through a slot provided in the upwardly extended leg of the pair, said seat being reduced in width at its rear end and 55 projecting through a slot in said back and means to lock said back to said seat.

5. A collapsible chair and easel having, in combination, a seat comprising a single rigid member, an arm projecting upwardly from the front end thereof and foldable into a slot extending longitudinally of said seat, said arm constituting a support for a drawing or the like, a leg attached to the front end of said seat, a pair of intersecting legs 60 attached to the rear end of said seat, one of said intersecting legs being reduced in width at its lower end and projecting through a slot provided in the other of said intersecting legs.

6. A collapsible chair and easel having, in combination, a seat provided with a slot extending longitudinally thereof, a brace extending transversely of said seat and attached to the lower side thereof, an arm 70 hinged to said seat and projecting through said slot, the lower end of said arm bearing against said brace when the arm is in an inclined vertical position, the portion of the arm extending above said seat constituting 75 a support for a drawing or the like, a leg hinged to said brace, a pair of intersecting legs adjacent to the rear end of said seat, a second brace extending transversely of 80 said seat upon the underside thereof, means 85 to attach the upper end of one of said intersecting legs to said second brace, the lower end of said last-named leg being reduced in width and projecting through a slot provided in the other of said intersecting legs, 90 the last-named leg being extended upwardly against said seat and forming a back therefor, the rear end of said seat being reduced in width and extending through a slot provided in said back leg and means to lock 95 said back leg to said seat.

In testimony whereof I have hereunto set my hand.

WILLIAM J. STEWARD.
